(57) **CLAIM**

The ornamental design for a beverage device, as shown and described.

DESCRIPTION

FIG. 1 is an isometric view of a beverage device, showing our new design;

FIG. 2 is another isometric view thereof;

FIG. 3 is a left side view thereof;

FIG. 4 is a right side view thereof;

FIG. 5 is a top view thereof;

FIG. 6 is a bottom view thereof;

FIG. 7 is a front view thereof;

FIG. 8 is a back view thereof; and,

FIG. 9 is a right side view thereof, in use condition.

The broken lines in FIG. 9 depict environmental subject matter only and form no part of the claimed design.
